CLAIM

The ornamental design for a lawn mower control handle, as shown.

DESCRIPTION

FIG. 1 is a top, front, and right side perspective view of a lawn mower control handle showing our new design. The broken line elements of FIG. 1 are for illustrative purposes only, and form no part of the claimed design.

FIG. 2 is a front elevational view thereof;

FIG. 3 is a top plan view thereof;

FIG. 4 is a bottom plan view thereof;

FIG. 5 is a right side elevational view thereof;

FIG. 6 is a rear elevational view thereof; and,

FIG. 7 is a left side elevational view thereof.

UNITED STATES PATENT AND TRADEMARK OFFICE
Certificate

Patent No. D 424,578

Patented: May 9, 2000

On petition requesting issuance of a certificate for correction of inventorship pursuant to 35 U.S.C. 256, it has been found that the above identified patent, through error and without deceptive intent, improperly sets forth the inventorship.

Accordingly, it is hereby certified that the correct inventorship of this patent is: Nathan J. Friberg, Bloomington, MN; David J. Martin, Eden Prairie, MN; Anthony N. Pink, Prior Lake, MN; Larry W. Schmidt, Farmington, MN; Philip G. Stalpes, Hamel, MN; and Chadwick A. Shaffer, Oakdale, MN.

Signed and Sealed this Thirteenth Day of August, 2002.
